UNITED STATES PATENT OFFICE.

MOUBRAY GORE FARQUHAR AND ARTHUR HENRY HILL, OF BIRMINGHAM, ENGLAND.

AUTOMATIC FIREARM.

1,350,961.

Specification of Letters Patent. Patented Aug. 24, 1920.

Application filed April 15, 1919. Serial No. 290,267.

To all whom it may concern:

Be it known that we, MOUBRAY GORE FARQUHAR and ARTHUR HENRY HILL, subjects of the King of Great Britain, residing at 5 Birmingham, in the county of Warwick, England, have invented certain new and useful Improvements in or Relating to Automatic Firearms, of which the following is a specification.

- 10 Our invention consists of the new or improved construction and arrangement or combination of parts hereinafter described of automatic fire arms, the said new or improved construction and arrangement of 15 parts having for their object to render the automatic fire arms patented to us on U. S. Patents Nos. 920,301 May 4th 1909, and 1,019,620 March 5th 1912 suitable for use as a machine gun.
- 20 According to the present invention we employ the breech opening spring or springs and breech closing spring of the patented automatic fire arms hereinbefore referred to arranged under the barrel of the gun as 25 heretofore, but the body and bolt cover are inverted, that is to say, the breech opening in the body which is closed and opened by the sliding of the bolt cover is presented downward and the cartridges are fed into 30 the cartridge chamber from a magazine, belt or other cartridge feed mechanism situated and working over the body or shoe of the gun.

We will further describe the said invention in connection with the accompanying drawing Figure 1 of which represents in side elevation the complete machine gun constituting our invention; Fig. 2 is a plan of the same and Fig. 3 a front elevation.

40 Figs. 4 and 5 are sectional views of portions of the gun drawn to a larger scale than Figs. 1, 2 and 3.

The same letters of reference indicate the same parts in the several figures of the drawing.

45 *a* is the trigger of the gun situated under the body or shoe *b* on which the sliding breech closing cover *c* works. The trigger guard *d* is or may be in one with an arm 50 or stay *d*¹ pivoted at *d*² to the rear seating *w*¹ for the spring containing tube or case *w* of the previously patented automatic

mechanism hereinbefore referred to and fastened at its rear end to the body cap *e* by the pin *f*. The tube seating *w*¹ is preferably screwed on to the front end of the body or shoe *b*.

The stock butt *g* which may be of the ordinary gun shape is attached to the body cap *e* and the trigger guard *d* is preferably provided with a pistol grip *h*. The motion of the trigger *a* when pulled is transmitted to the part of the firing mechanism situated in the lock case *i* over the body or shoe *b* by means of a lever *k* (or equivalent device) 65 situated and working in the body cap *e*.

The lock or firing mechanism represented is constructed so that the gun can be fired automatically or continuously and when desired can be arranged for single fire, that is 70 to say, to fire one cartridge for each pull on the trigger.

The firing mechanism comprises a hammer *l* arranged so as to hang or depend from the pivot *m* as will be seen by an examination of Figs. 4 and 5. The hammer spring *l*¹ bears on a projection or heel piece near the pivot *m*. The said hammer *l* has two bents marked respectively *l*¹, *l*² to engage with which bents the spring pressed sliding sear *n* and projection *u*¹ on the external pivoted sear or lever *u* are provided the sliding sear *n* being operative only when the gun is set for single fire and the pivoted sear *u* being operative when the gun is 85 arranged for automatic or continuous fire.

The sliding sear *n* is connected with the trigger *a* through the lever *k* and spring pressed link *p* which latter has a hook-like part *p*¹ which engages with the shoulder *n*¹ 90 at the rear end of the sliding sear *n*.

Adjacent the trigger *a* is a spring pressed lever *a*¹ having a projection *a*² on its upper edge which projection, when the trigger *a* is in its normal position, projects into the 95 path of the projection *c*² on the underside of the bolt cover *c* and serves to retain the said cover *c* and bolt in their retracted position on the initial cocking of the hammer *l* or when the trigger is released after 100 firing.

For automatic or continuous fire the trigger *a* is held in its pulled back position in which position it effects the retraction of

the sliding sear n thereby preventing the bent l^1 of the hammer l engaging therewith, the hammer under these conditions being retained cocked by the engagement of the bent l^2 with the projection u^1 of the external sear u which projection u^1 occupies and works in a slot in the lock case the acting end projecting into the path of the hammer l . The external sear u is automatically tripped for effecting the removal of the projection u^1 from the bent l^2 by a lug c^1 on the sliding cover c , each time the cover in its forward motion is about to effect the closing of the breech and as the reciprocation of the cover under the action of the mechanism of the prior patents hereinbefore referred to is automatic, and continuous automatic fire results.

On the release of the trigger a the sear n returns under the action of its spring into the position for engaging with the bent l^1 of the hammer l when the same is cocked on the rearward motion of the sliding bolt and cover c .

When it is desired to fire one cartridge only for each pull on the trigger a a transverse spindle r situated under the link p and having a notch or cut away part adjacent the said link is turned through a half rotation so as to bring the convex side of the notched part into contact with the link p , the flat side being downward. The said spindle r in this position effects, when the link p and sear n are pulled back by the operation of the trigger a , the lifting of the front part of the link p adjacent the sear n against the action of the spring s , the link p escaping or slipping out of engagement with the sear n and allowing the said sear to return into position for reengaging the hammer l when again cocked by the backward motion of the bolt for effecting the extraction of the spent cartridge.

On the semi-rotation of the transverse spindle r for bringing the flat of the notched part uppermost as is represented in Fig. 4 the sear n and link p remain permanently engaged and consequently on pulling the trigger a continuous or automatic fire results until the trigger a is released or the magazine (not shown) or equivalent cartridge feed device is emptied.

The safety device for the firing mechanism consists of a lever t one of the arms of which, when in its operative position bears on the lever k through which the motion of the trigger a is transmitted to the part of the firing mechanism over the body or shoe b and thereby blocks the said lever k and trigger a and renders them immovable.

On opposite sides of the body cap e are projections or lugs e^1 in which projecting spring pressed buffers e^2 for the breech cover c are arranged the said buffers e^2 absorbing the shock when the cover is forced back and

assisting the bolt closing spring of the prior patented automatic mechanism to return the cover c to the bolt closing position.

The arm or link v by which the action of the springs of the automatic mechanism is transmitted to the sliding cover c is arranged between the barrel x and spring containing tube or case w instead of on one side of the gun as heretofore.

We preferably arrange over the spring y^1 which actuates the catch y of the automatic mechanism a metallic sheath or cover z indicated in dotted lines in Fig. 1.

On a girder-like bar 1 fastened at its rear end to the tube seating w^1 and supported at its front end by the fore end cap is a slide 2 carrying two inclined trunnions or pins 3, 3 on which a pair of legs 4, 4 are jointed the said legs in their out of use position being parallel and situated close or nearly close together under the girder-like bar 1 referred to and being fastened by a spring snap fastening 5 or the like. By operating the spring snap fastening and thereby releasing the legs 4, 4 they fall forward by 90 their own weight and automatically take the open or spread out position represented in Figs. 2 and 3.

We prefer to employ a rotary cartridge magazine of the kind described, represented and claimed in the complete specification of our pending application Serial No. 268968 which magazine is arranged on the pivot 6 situated on the upper end of the tube seating w^1 which is fastened on the front end of the body b and the cartridge magazine is preferably secured in position by the spring pressed lever 7 on the front end of the lock case i situated over the body b .

The back sight 8 is arranged on the lock case i and being elevated with respect to the body b the foresight 9 is made capable of turning on a pivot 10 so that it can be turned up into position for use as illustrated in Figs. 1 and 3, or turned down into a horizontal position over the barrel when the gun is not in use, a spring pressed slide with V shaped acting end engaging in one or other of the V shaped notches to firmly fix the foresight in one or other of the two positions.

When the gun is to be used on a fixed mounting for which trunnions 11, 11 are provided the stock butt and pivoted legs 4, 4 hereinbefore described may be dispensed with.

We claim:—

1. In an automatic fire arm the combination with a body having a sliding breech closing cover arranged thereon and operating the bolt to give it a backward and forward sliding motion, a depending hammer pivoted over the body and mechanism arranged over the body for retaining the said hammer in the cocked position against the action of its spring, said mechanism comprising spring 128

pressed pivoted and sliding elements connected at their rear ends to a pivoted lever at the end of one arm of which bears on the trigger lever.

- 5 2. In an automatic fire arm the combination with a body having a sliding breech closing cover arranged on the underside of the body and operating the bolt on its backward and forward sliding motion, a lock case supported on said body, a depending hammer pivoted in the lock case over the body having two bents, an internal sliding sear for engaging one of said bents and a projection on an external pivoted sear for 10 engaging the other bent, said projection working in a slot in the lock case, a lever and spring pressed link for operating the internal sear from the trigger and a projection on the sliding breech closing cover for operating the external sear, the external sear 15 acting when the trigger is held back for the purpose of obtaining continuous fire.

3. In an automatic fire arm the combination with a body having a sliding breech closing cover arranged on the underside of the body and operating the bolt on its backward and forward sliding motion, a lock case supported on said body, a depending hammer pivoted in the lock case over the body having two bents, an internal sliding sear for engaging one of said bents and an external pivoted sear for engaging the other bent, said external sear having a projection working in a slot in the lock case, a lever and spring pressed link for operating said internal sear by the trigger and a projection on the sliding breech closing cover for operating said external sear, the external sear 25 acting when the trigger is held back for the purpose of obtaining continuous fire, the sliding link of the internal sear having in combination therewith means operating when the mechanism is set for single fire for disengaging the said link from the sear 30 when the latter is actuated to the extent proper for releasing the hammer.

4. In an automatic fire arm the combination with a body having a sliding breech closing cover arranged on the underside of the body and operating the bolt on its backward and forward sliding motion, a lock case supported on said body, a depending hammer pivoted in said lock case having two bents, an internal sliding sear for engaging one of said bents and a projection on an external pivoted sear for engaging the other bent, said projection working in a slot in the lock case, a lever and spring pressed link for operating the internal sear and a 35 projection on the sliding breech closing cover for operating the external sear, the external sear acting when the trigger is held back for the purpose of obtaining continuous fire, the sliding link of the internal sear having means operating when the 40

mechanism is set for single fire for disengaging the said link from the sear when the latter is actuated to the proper extent for releasing the hammer, a spring pressed catch co-operating with the trigger and adapted 70 to engage a projection on the sliding cover when the trigger is released and the cover is pressed into the breech opening position by the automatic mechanism of the fire arm.

5. In an automatic fire arm the combination with a body having a sliding breech closing cover arranged on the underside of the body and operating the bolt on its backward and forward sliding motion, a depending hammer pivoted over the body having two bents, an internal sliding sear for engaging one of said bents and an external pivoted sear for engaging the other bent, said external sear having a projection working in a slot in the lock case, a lever and spring pressed sliding link for operating the internal sear from the trigger and a projection on the sliding breech closing cover for operating the external sear, the external sear acting when the trigger is held back 80 for the purpose of obtaining continuous fire, the sliding link of the internal sear having means operating when the mechanism is set for single fire for disengaging the said link from the sear when the latter is drawn back 90 to the extent proper for releasing the hammer, a spring pressed catch adjacent the trigger which engages with a projection on the sliding cover when the trigger is released and the cover is pressed into the breech opening position by the automatic mechanism of the fire arm, and a safety lever one of the arms of which when in its operative position bears on said lever and locks the trigger in inoperative position. 95

6. In an automatic fire arm the combination with a body having a sliding breech closing cover arranged on the underside of the body or shoe, a link connected at its rear end to said cover and at its forward end to the rear of the breech opening spring of the automatic mechanism, said link being situated and working between the underside of the barrel and the spring containing tube of the automatic mechanism and operating the 110 breech cover to open and close the breech, a depending hammer pivoted over the body and mechanism arranged over the body for retaining the said hammer in the cocked position against the action of its spring, 115 said mechanism comprising spring pressed pivoted and sliding elements connected at their rear end to a pivoted lever bearing at one end on the trigger lever.

7. In an automatic fire arm the combination of a sliding cover, a hammer automatically placed in cocked position, a sliding sear and a pivoted sear for releasably maintaining said hammer in cocked position, manual means including a pivoted 125

130

lever and a sliding link for releasing said sliding sear from the hammer, and a lug on said cover adapted to release said pivoted sear just prior to the closing of the breech 5 by said cover.

8. In an automatic fire arm the combination of a trigger, a sear, a pivoted lever and sliding link actuated by said trigger for manually releasing said sear, means coöperating 10 with said sliding link for releasing the latter from the control of said trigger, said means being movable to restore said

link to operative position for automatic firing and a safety device adapted to act on said lever to lock the trigger in inactive 15 position.

In testimony whereof we have hereunto set our hands in presence of two subscribing witnesses.

MOUBRAY GORE FARQUHAR.
ARTHUR HENRY HILL.
